PER CENT TO FRANK G. CAMPBELL

METHOD OF AND APPARATUS FOR LIQUEFYING GASES

Application filed March 27, 1930. Serial No. 439,435.

This invention relates to a new process for the liquefaction of air and other gases, having an extremely low condensing temperature, and contemplates a near approach to the minimum theoretical work necessary to accomplish the liquefaction of such gases.

A further object of the invention is to eliminate counter-current piping, except in conjunction with the heat exchange in the working medium, for removing the latent heat of the condensing vapor, which medium is contained in a closed circuit being compressed at a convenient or easily attained temperature, cooled in the usual way and passed counter-current to the same medium in the expanded state. By virtue of this I am able to obviate the formation of frost, constituting one of the highly objectionable features of known processes, on the inside surface of the piping.

The invention also contemplates the performance of external work by the superheat of the gas to be liquefied, thereby increasing the efficiency of the process, as a whole, and more particularly increasing the efficiency of the unit employed for the conversion of the superheat of the gas into mechanical work.

I am aware of the fact that this feature alone is not new in the art, but am, at present, unaware that the prior art anticipates the removal either of the superheat or the heat of vaporization, in this manner, without first cooling the compressed gas to be liquefied in counter-current with the expanded gas. This lowers the efficiency of the engine or turbine by which the superheat of the gas is being converted into useful work by a well known thermo dynamic law.

Another very useful application of the invention resides in the separation of helium from natural gas, the heavy hydrocarbons being disposed of in the manner hereinafter described for the water vapor content of air, leaving chiefly nitrogen and methane to be liquefied in the manner in which nitrogen and oxygen are liquefied, as hereinafter described, the helium being left as uncondensed residue.

It may be objected that this invention contemplates primarily the cheap quantity lique-

faction of gases and that the separation of helium is more a problem of distillation or rectification not dependent upon cheap quantity production of liquefied gas for its success. In this connection it should be borne in mind that methane CH_4 , the chief constituent of helium bearing natural gases, due to its relatively large proportion of hydrogen furnishes a great deal more heat units per unit of weight than does gasoline. Therefore, liquid methane could be carried in suitable thermos tanks upon aeroplanes and furnish a much lighter fuel for air craft than any now economically possible. This feature I regard as much more important than the separation of the helium.

Another important economic aspect of the invention is that it renders possible the production of liquid oxygen at such a cost as to render the widespread use of said liquid oxygen, as an explosive, commercially practicable. Aside from this, the delivery of oxygen from manufacturer to consumer could be greatly facilitated by delivery in the liquid state, thereby greatly reducing both the gross weight handled and the bulk of the delivery containers.

The invention contemplates the removal of the total heat of the vapor in two distinct steps: First, the removal of the superheat of the vapor by adiabatic expansion, preferably, against a turbine, the expansion taking place so suddenly that a close approach to a pure adiabatic expansion occurs. Second, the removal of the latent heat condensation by expanding in a plurality of stages a gas having a critical temperature considerably lower than the condensing temperature of the vapor, preferably, against moving surfaces, to obtain a closer approach to isothermal expansion, and returning the expanded gas to the compressor countercurrent, with the compressed gas supplying the engine.

One form of apparatus which I may employ in carrying out the process above described is illustrated in the accompanying drawing, wherein,

Fig. 1 is a diagrammatic view,

Fig. 2 is a sectional view through one of the turbines hereinafter described,

Fig. 3 is an oblique sectional view upon line 3—3 of Fig. 1,

Fig. 4 is an enlarged sectional view through the condenser, and

Fig. 5 is a transverse sectional view through the condenser.

Like numerals designate corresponding parts in all the figures of the drawings.

I will describe the application of the apparatus in its relation to the liquefaction of air. Its applicability in the other relations hereinbefore described will then be readily apparent to those skilled in the art.

In the drawing, 5 designates an air compressor of any suitable form, here conventionally shown as an ordinary piston air compressor. The air compressed by the compressor is conducted by a pipe 6, to a turbine 7, the pipe passing through a suitable water cooler, 20 at 8. The gases are delivered to the turbine 7 through the nozzle 9 (see Fig. 3). It will be observed that the pipe 6 is restricted, as indicated at 10, at a point outside of the turbine. By virtue of this arrangement I am able to 25 prevent the objectionable frosting which so frequently occurs in other liquefaction apparatus, at present employed. This is due to the fact that the restricted portion of the pipe 10 is located at such a point that it will always 30 be at a higher temperature than the temperature of the expanding gases, and, consequently, the frost crystals will not adhere thereto. Furthermore, this nozzle is insulated against 35 heat losses by elements 18 and 19, hereinafter described. The impingement of the gases from the nozzle 9 upon the blades 11 of the moving rotor 12, that is carried by shaft 13, prevents the reversion of the energy of the 40 gases into heat. With expansion taking place suddenly a condition of super saturation of the water vapor content of the air would occur, so that the frost crystals would not form until after impingement of the jet on the rotor blades, and then would 45 not adhere to the containing walls, being formed in the air and carried along with it.

The motion of the shaft 13 may be utilized in the performance of any useful work, as, for example, in the driving of the compressor 5, or otherwise. The construction of the turbine 7 may be widely varied. One type of construction is illustrated in Fig. 2, where 12 designates the rotor on shaft 13, said rotor being provided with the blades 11, and being received within the space between the two casing sections 16 and 17. A jacket 18 is formed about these sections in which a vacuum is maintained, and, in addition, these jackets may be more or less filled with sheets 60 of metal foil, indicated at 19. These metal foil sheets serve to resist the passage of heat by radiation, and the vacuum serves to prevent the passage of heat by either conduction or convection. However, suitably insulating 65 the various parts of apparatus of this char-

acter against heat losses is manifestly within the skill of the refrigerating engineer, and I contemplate insulating the apparatus against such heat losses to whatever extent may be found necessary, in practice. The expanded gases pass through a pipe 20, to the interior of the condenser, indicated, as a whole, at 21. This condenser comprises a casing 22, which is jacketed and heat insulated in the manner previously described, with respect to the turbine of Fig. 2. Located within the casing 22 is a group of any desired number of turbines 23, the rotors of which are mounted upon the common shaft 24. The shaft may be carried to the exterior of the condenser and used to do any useful work through the medium of the pulley, indicated at 25, or otherwise. The casing of each turbine is connected through a suitable pipe coil 26, with the casing of the next succeeding turbine, and the casing of the mechanically driven compressor 27, which is substantially the same as the compressor 5, is used to compress an independent gas medium such as hydrogen, having a critical temperature lower than the condensing temperature of the gas sought to be liquefied, and delivers the same through a run of pipe 28, to the casing of the first turbine of the group, in the condenser 22. The expanded refrigerating medium from the last stage or the last turbine is conducted through a pipe 29, and, preferably, counter-current to the flow of gas in pipe 28, back to the hydrogen compressor 27, where it is re-compressed and the cycle repeated. A breather hole 20' may be left in the pipe 20 to compensate for variations in the efficiencies of the two units represented, respectively, by the elements 5 and 7, on the one hand, and the elements 27 and 22 and associated parts, upon the other hand. If the condensing capacity of the latter unit is greater than the delivery capacity of the units 5 and 7, additional air will be drawn through the breather hole to compensate for the deficiency, while, if the reverse is the case, the surplus expanded gas would be discharged through said opening 25.

To provide for access to the interior of the condenser 22, while, at the same time, providing the maximum degree of insulation against heat losses, I provide the interior casing with a removable cover 22^a, and the outer casing with a removable covering 22^b, the space between the two constituting a vacuum jacket 22^c, and said space receiving any suitable number of sheets of metal foil indicated at 22^d. The inner and outer casings may be held in properly spaced relation to each other by spacing balls 22^e, of a material such as porcelain, having a low degree of heat conductivity, while, at the same time, possessing the requisite strength for the purpose.

According to the Millar and Sullivan technical paper 424, issued by the Bureau of

Mines, the entropy of nitrogen, the chief constituent of air, is the same at 60 atmospheres and 271° K. as at one atmosphere at saturation temperature. Therefore, theoretically, with adiabatic expansion taking place 5 at constant entropy, an air pressure of 60 atmospheres delivered by the compressor at 271° K. would be sufficient to completely remove the superheat of the vapor. With a turbine of high mechanical efficiency, the necessary air pressure would not greatly exceed this amount.

From the data furnished by Millar and Sullivan on the total heats of nitrogen vapor and the formula for isothermal compression of gases, it is easy to calculate the theoretical work required for this removal of the superheat in the manufacture of liquid air, which would be the works of isothermal compression less the work of adiabatic expansion, which per pound of nitrogen would be 108,700 foot pounds and 63,900 foot pounds, respectively, leaving a net expenditure of only 44,800 foot pounds.

25 The air that is delivered through pipe 20, and which has had its superheat removed, is brought into heat exchanging relation with the coils connecting the expansion stages of the several turbines, wherein a gas, viz: the 30 hydrogen having a low critical temperature, is being expanded and contacting with the numerous convolutions of the pipe coils it condenses to liquid form, its latent heat being given up to maintain isothermal expansion.

35 Due to the low critical temperature of the expanding gas medium, no condensation of the medium can occur, thus, rendering nearly perfect the transformation of heat into work. Since the work of isothermal compression or expansion between two given pressures is proportional to the volume of the gas, and, consequently, to the absolute temperature and the heat given up or absorbed 40 being equal to the mechanical equivalent of the work done, and the net work expended being equal to the difference between isothermal compression and isothermal expansion, the following formula would apply:

$$50 W = \frac{Ht}{t'} - \frac{Ht'}{t} = H(t-t').$$

In this formula, W is the net work expended; H the mechanical equivalent of the heat absorbed; t the temperature of isothermal compression, and t' the temperature of isothermal expansion. The heat capacity of the gas medium between the temperatures t and t' need not be taken into account, since it is given up to the expanded gas in the counter-current or heat exchange coils 28 for the temperature of the gas medium being always far above its critical temperature, the greater pressure of the gas supplying the expansion engines within the condenser will not

operate to materially increase its heat capacity over the heat capacity of the expanded gas. Applying the data furnished by Millar and Sullivan on the thermal properties of nitrogen to this formula, I obtain 177,460 foot pounds as the theoretical net work of removing the latent heat of 1 pound of nitrogen vapor. This, added to the net work of removing the superheat gives 222,260 foot pounds as the minimum theoretical net work of liquefying one pound of nitrogen vapor.

With good heat insulation and efficient compressors and expanders, the actual expenditure of energy should not exceed 300,000 foot pounds per pound, which would mean an output of 4.9 liters per kilowatt hour against .95 liters which at present is considered good.

While the apparatus herein shown and described represents one embodiment which may be utilized in carrying out my ideas, it is to be understood that the invention is not limited to this apparatus, nor to any specific type of apparatus, since many ways of accomplishing the same result will readily suggest themselves to those skilled in the refrigerating art. Consequently, it is to be understood that the invention includes within its purview whatever changes fairly come within either the terms or the spirit of the appended claims.

Having described my invention, what I claim is:

1. The herein described process of absorbing and removing the latent heat of condensation of gases having a low condensing temperature, which consists in compressing a gas having a critical temperature lower than the condensing temperature of the gas sought to be liquefied, expanding the said gas while in heat exchanging relation with the saturated vapor, and returning the expanded gas in counter-current with the compressed gas to its source of compression.

2. The herein described process of absorbing and removing the latent heat of condensation of gases having a low condensing temperature which consists of compressing a gas having a critical temperature lower than the condensing temperature of the gas sought to be liquefied, expanding said gas substantially isothermally against an external resistance while in heat exchanging relation to the saturated vapor, and returning the expanded gas in counter-current with the said gas to its source of compression.

3. The process of removing the superheat of gases comprising compressing the gas to a pressure where its entropy at a convenient temperature is equal to or less than its entropy of saturation and expanding substantially adiabatically against an external resistance.

4. The herein described process of removing the total heat of a gas above the heat of

the liquid, which consists in compressing and expanding the said gas from a convenient temperature against a suitable external resistance for the purpose of partially or completely removing the superheat of the gas, and subsequently bringing the gas thus cooled in heat exchanging relation with a pre-cooled gas medium which is expanded against an external resistance and has a critical

temperature lower than the condensing temperature of the said gas for the purpose of absorbing the remaining total heat content above the heat of the liquid.

5. The herein described process of removing the superheat of gases, having a very low condensing temperature, which consists in compressing the gas and expanding the same substantially adiabatically from a convenient temperature against an external resistance preparatory to the removal of its latent heat of condensation, by other refrigerating means.

6. The adiabatic expansion of compressed air against external resistance, for the removal of its superheat and the subsequent removal of its latent heat of condensation at constant temperature by refrigerating means.

7. Apparatus of the character described, comprising a gas compressing and expanding means, a condenser to which the expanded gas is delivered, a second gas compressing means, a second gas expanding means within the condenser, a conduit through which the gas from the second gas compressing means is delivered to the gas expanding means within the condenser, and means for conducting the expanded gas from the last named gas expanding means counter-current along said conduit, and back to the second gas compressing means.

8. A structure as recited in claim 7 wherein the second gas expanding means within the condenser is of multiple stage.

9. Apparatus of the character described, comprising a compressor for gas to be liquefied, an expander to which the gas is delivered from said compressor, and a condenser to which the gas is delivered, said condenser comprising a plurality of expansion engines.

10. Apparatus of the character described, comprising a compressor for gas to be liquefied, an expander to which the gas is delivered from said compressor, and a condenser to which the gas is delivered, said condenser comprising a plurality of expansion engines, having a common shaft.

11. A structure as recited in claim 9, wherein the several engines are connected in series with each other by independent refrigerating coils, the whole constituting a multiple stage expansion apparatus.

12. A structure as recited in claim 9, in combination with a second gas compressing apparatus, means for delivering the gas compressed thereby to and conducting said gas

in series through the several stages of expansion provided by a plurality of expansion engines, means for returning the gas from said expansion engines to the second gas compressing apparatus, and means for subjecting the gas that is traveling to said engines to the action of the gas that is being returned from said engines, in heat exchanging relation between the two.

13. Apparatus of the character described, comprising a compressor for gas to be liquefied, an expansion engine to which said gas is delivered, a condenser to which the gas is delivered from the expansion engine, said condenser comprising a plurality of expansion engines connected in series by refrigerating coils to the action of which the gas from the first named expansion engine is subjected, a compressor for a gas having a critical temperature lower than the condensing temperature of the gas that is being liquefied, means for conducting the last named gas to the expansion engines of the condenser, and means for returning the gas from said expansion engines to the second compressor in counter-current to the flow of gas from said compressor to the said plurality of expansion engines.

14. In the quantity production of liquefied gases, the herein described process of absorbing and removing the latent heat of condensation of gases having a low condensing temperature, which consists in compressing a gas having a critical temperature lower than the condensing temperature of the gas sought to be liquefied, expanding the said gas while in heat exchanging relation with the saturated vapor, and returning the expanded gas in counter-current with the compressed gas to its source of compression.

In testimony whereof I affix my signature. 105
